(57) **CLAIM**

The ornamental design for medical injector support pad, as shown and described.

DESCRIPTION

FIG. 1 is a front and top left side perspective view of a medical injector support pad housing;

FIG. 2 is rear and bottom right side perspective view thereof;

FIG. 3 is a top and front perspective view thereof;

FIG. 4 is a bottom and back perspective view thereof;

FIG. 5 is a left side elevation view thereof;

FIG. 6 is a right side elevation view thereof;

FIG. 7 is a front elevation view thereof; and

FIG. 8 is a back elevation view thereof;

FIG. 9 is a top plan view thereof; and,

FIG. 10 is a bottom plan view thereof.

The broken lines show portions of the medical injector support pad that form no part of the claimed design.
